UNITED STATES PATENT OFFICE

131,692

DESIGN FOR A BOTTLE

Allen D. Strahm, Tulsa, Okla.

Application July 5, 1941, Serial No. 101,926

Term of patent 14 years

To all whom it may concern:

Be it known that I, Allen D. Strahm, a citizen of the United States, residing at 3020 South Madison Avenue, in Tulsa, county of Tulsa, and State of Oklahoma, have invented a new, original, and ornamental Design for a Bottle, of which the following is a specification, reference being had to the accompanying drawing, forming a part thereof.

The figure is an elevational view of a bottle, showing my new design. The rear of the bottle is substantially the same as the front, and the bottle is of circular cross-section throughout.

I claim:

The ornamental design for a bottle, as shown and described.

ALLEN D. STRAHM.
